PORTABLE LOG SAWING MACHINE

John E. McLeod, Wellaston, Mass., assignor to
Great Northern Paper Company, Millinocket,
Maine, a corporation of Maine

Application March 9, 1935, Serial No. 10,217

3 Claims. (Cl. 143—43)

This invention relates to portable log sawing machines adapted to be moved from place to place to cut logs into short lengths suitable for conversion into paper pulp.

5 A common method of preparing logs for pulp wood comprises felling the trees wherever they may stand and hauling the long logs either by dragging or by loading on sleds or in any other convenient manner to a so-called yard where 10 the logs are piled and are subsequently sawed, heretofore by hand, into four foot lengths or other suitable lengths for conversion into paper pulp, the short lengths usually being hauled to a stream or landing and floated to the pulp mill. 15 A tract that is being cut for pulp wood may have several log storage yards distributed at locations suitable for the logging operation. Heretofore, it has been the best practice to cut the logs into short lengths by hand. This method, however, 20 is slow unless a large force of men is provided, and is relatively expensive.

An object of the present invention is the provision of a log sawing machine that is arranged to cut the long logs into short lengths suitable 25 for pulp manufacture, the machine being portable and especially adapted for movement over rough terrain and having short width and small height so that it can be moved between closely spaced trees and over winding logging roads to 30 the log yards and placed in position beside the log piles for sawing them into the shorter lengths.

A further object of the invention is a portable log sawing machine of the type described, comprising a circular saw, a power plant for driving the saw and the associated mechanism, and feeding devices for advancing the log toward the saw.

The machine of the invention is composed of 40 a plurality of sections arranged in tandem, the sections having log-feeding mechanisms so that long logs can be supported and advanced toward the saw and being articulated so that the machine can be moved freely along winding roads 45 and between closely spaced trees and over uneven ground. The machine also is so arranged as to operate satisfactorily upon the log notwithstanding any small misalignment of its articulated sections, it being appreciated that it is not 50 always practicable to select long reaches of level ground in which to yard the logs and hence the machine must be capable of handling the logs even if the articulated parts are somewhat out of line. Such a machine constitutes an object 55 of the invention.

A further object of the invention is the provision of a portable sectional log sawing machine, one section containing the saw, the power plant, and a portion of the log advancing mechanism, and a second section being articulated to the 5 first section and containing a further part of the log advancing mechanism, which mechanism is driven by the power plant of the first section and so arranged as to cooperate with the log advancing mechanism of the first section to advance the log to the saw.

Another object is generally to improve the construction and operation of portable log sawing machines.

Fig. 1 is a perspective view of a portable log 15 sawing machine embodying the present invention.

Fig. 2 is a side elevation of the main section of the machine that comprises the saw and the power plant.

Fig. 3 is a plan view of the machine of Fig. 1.

Fig. 4 is a sectional detail taken along line 4—4 of Fig. 2.

Fig. 5 is a sectional detail taken along line 5—5 of Fig. 2 and illustrating especially the 25 log stop mechanism.

Fig. 6 is a sectional detail taken along line 6—6 of Fig. 2 and illustrating particularly the friction drive and brake mechanism for controlling the swing movements of the saw.

Fig. 7 is a sectional detail taken along line 7—7 of Fig. 3 and illustrating particularly the driving mechanism for the log advancing rolls.

Fig. 8 is a sectional detail taken along line 8—8 of Fig. 3 and illustrating an eccentric bushing 35 for controlling the engagement of the friction wheels for swinging the saw.

Fig. 9 is a plan view of the trailer sled.

The portable log sawing machine embodying the present invention comprises a saw sled 10 40 and a trailer sled 12. The saw sled, see especially Figs. 1, 2 and 3, is composed of a frame or chassis having longitudinal side girders in the form of I beams 14 and cross beams 16. The frame is mounted upon skids or runners 18 on which the 45 side beams 14 rest. The trailer sled is similarly formed with a frame comprising the longitudinal I beams 20 and cross beams 22 and has skids or runners 24 under the longitudinal beams. The trailer sled at its forward end is provided with 50 a tongue 26 that is pivoted to the similar ends of the side beams 20 and engages a king pin 28 of the saw sled so that the two sleds are flexibly connected together in tandem, or are articulated, and can be drawn freely along winding woods 55

roads and between closely spaced trees and over rough uneven terrain. The saw sled at its forward end is provided with a tongue 30 similar to the tongue 26 by which the connected sleds can be connected to a tractor and drawn from place to place. The saw sled contains the cut-off swing saw, a portion of the apparatus for advancing the logs to the sawing position, the power plant for operating the mechanism and the control means for governing the operation of the mechanism. The trailer sled carries the remaining portion of the log advancing mechanism and is intended to be spaced from the saw sled by a sufficient distance so that the machine can handle the long logs that are to be cut up into shorter lengths suitable for conversion into pulp. Ordinarily the tongue 26 is of sufficient length to space the two sleds a convenient distance apart, although if the machine is required to operate upon a collection of unusually long logs the tongue can be detached from the trailer sled and the sleds separated a suitable distance.

The log advancing mechanism on the saw sled comprises a series of feed rolls 32 suitably journaled on the frame of the sled and located near the front side of the sled with their axes arranged transversely of the frame. A guide plate 34 extends longitudinally of the saw sled above the inner ends of the rolls, against which the log is adapted to bear during its advancement into cut-off position and while being engaged by the saw. The guide plate is supported in position by suitable brackets 36 carried by the transverse beams 16, see especially Fig. 7. The feed rolls 32 are preferably tapered in diameter and have a smaller diameter near the guide plate 34 and a larger diameter near the front edge of the machine. This arrangement provides the rolls with upper log engaging surfaces that slope downwardly toward the guide plate and thereby tend to hold the log engaged by gravity with the guide plate. The rolls are preferably provided with driving projections or studs 38 that bite into the log and thus positively engage it for endwise movement.

A sawdust chute in the form of a channel member 40 is provided at the sawing position, the chute extending transversely of the sled to receive the sawdust and cause it to be discharged from the rear side of the plate.

A log deck 42 is provided on the other side of the chute 40. Said deck comprises essentially a flat plate, see especially Figs. 2, 3 and 5, inclined to correspond to the inclination of the top portions of the feed rolls and having a series of transverse openings 44 therein through which the upper portions of idler rolls 46 project. Said idler rolls 46 are suitably journaled and are adapted to receive and support the short length 60 of log that is severed from the longer portions and to permit the log to be moved readily in an endwise direction off the deck. An upstanding guide plate 48 is disposed at the inner ends of the rolls and has the functions of the previously described guide plate 34.

The logs are cut off into the shorter lengths by a swing saw 50 which is fixed to a shaft or arbor 52 journaled in suitable boxes carried by the upper ends of the parallel and normally vertically disposed side arms 54 of a swing frame. Said frame is provided with a pivot shaft 56 intermediate the ends and crosswise of the frame, which shaft is journaled in bearings 58, see especially Figs. 4 and 6, carried by the frame of the sled.

The saw frame thus can swing or pivot about the

cross shaft 56 as an axis to move its saw downwardly and transversely through the log. The saw frame 54 extends below the pivot shaft 56 and is provided with weights 60 which over-balance the overhung weight of the saw and thus tend to maintain the saw constantly in elevated position above and out of engagement with the log, as illustrated in Figs. 4 and 6.

The saw is driven by a shaft 62 carried by the frame of the machine coaxially with the pivot shaft 56. Said shaft 62 is provided with a driving pulley 64 and the saw shaft 52 is provided with a pulley 66. A plurality of independent belts 68 disposed in side by side order on the two pulleys serve to transmit power between the drive shaft 62 and the saw. Due to the concentric alignment of the drive shaft with the pivot shaft 56 the swinging of the saw does not affect the driving thereof and neither does the driving of the saw affect the swinging thereof. The shaft 62 is driven by a self-contained power plant comprising an internal combustion engine 70 through a clutch 72 and a speed reducing gearing 74. The clutch is operated by a manually controlled hand wheel 76 or the equivalent so that the power plant may be disconnected from the apparatus when desired while maintaining the power plant in operation.

The saw is reciprocated toward and away from the log or, stated more accurately, is moved downwardly through the log, by means of a crank shaft 78, journaled on transverse girders 16 of the frame under the saw and having a crank arm 80, see Fig. 3, terminating in a crank pin 82 that is journaled in the lower end of a connecting rod 84, see Figs. 4 and 6. Said connecting rod extends upwardly and is fixed to a transverse shaft 86 journaled in boxes 88 carried by the swing frame 54 near the upper end thereof and between the upper end and the pivot shaft 56. The stroke of the crank pin is such as to move the saw from its fully elevated position as shown in full lines Fig. 4, downwardly and below the top log engaging surface of the feed rolls, as shown in the dotted line position of the saw, Fig. 4, sufficiently to cause the saw to cut through any log on the rolls.

The crank shaft is rotated by the power plant 70. Said crank shaft is provided with a large gear 90 meshing with a pinion gear 92, see Fig. 3, fixed to a shaft 94 suitably journaled in cross members of the frame and having a large driven friction wheel 96 fixed thereto. A small driving friction wheel 98 is adapted to engage the surface of the cooperating friction wheel 96 and thereby rotate said wheel and the crank shaft. The driving friction wheel 98 is fixed to a shaft 100 that is connected through a universal joint 102 with a secondary drive shaft 104, which shaft 104 is driven through sprocket and chain mechanism 106 from the drive shaft 62.

The friction wheel 98 is moved into and away from engagement with the driven shaft by wheel 96 under control of an operative. To this end the shaft 100 adjacent the wheel 98 is journaled in an eccentric bushing, see Fig. 8, that is angularly rotatable in a bearing box 110 and has a laterally outstanding arm 112 by which the bushing can be rotated in the bearing block 70 to move the driving friction wheel 98 into and out of engagement with the cooperating driven wheel 96, the universal joint 102 permitting such movement.

The rotation of eccentric bushing 108 is accom-

75

plished by an operative located at the front side of the machine. A link 114 is pivotally connected at its inner end to the arm 112 of the eccentric bushing and at its outer end to an arm 116 of a 5 control tube 120 which is located at the front edge of the machine and extends longitudinally thereof and terminates in a vertically extended hand lever 122 disposed in front of the deck 42. Movement of the hand lever from a neutral or 10 mid position thereof inwardly or toward the saw effects the engagement of the friction wheels and the reciprocation of the saw.

When the saw has cut through the log the hand lever is adapted to be pulled backwardly through 15 its neutral position to effect the disengagement of the friction wheels so that the counterweights 60 return the saw to its elevated position. Further movement of the hand lever moves it into a braking position where it conditions brake 20 mechanism to check the return movement of the saw frame and to hold the saw in elevated position. The brake mechanism, see especially Figs. 3 and 6, comprises a flexible strap 124 which passes about the lower peripheral portion of the 25 friction pulley 96 and has its upper end anchored at 126 to the frame of the machine. The forward end of the strap is fixed to a link 123 that is pivotally connected to an arm 130 of the tube 120. Thus as said hand lever is moved away from 30 the saw the brake strap 124 is brought into frictional engagement with the driven friction wheel 96, thereby to check the retraction movement 35 of the saw frame and to hold it in elevated position.

The feed rolls 32 are driven by a shaft 132 that is extended lengthwise the battery of rolls and is 40 suitably journaled on the frame of the sled. Each of said rolls has a bevel gear 134 fixed thereto which meshes with a smaller gear 136 fixed 45 to said shaft. Said shaft is driven by a cross shaft 138 located at the rear end of the sled under the power plant. Said cross shaft has a bevel gear 140 that meshes with a gear 142 fixed 50 to the roll-driving shaft 132. The cross shaft 138 has a pair of confronting driven friction cones 144 and 146, respectively, fixed thereto. A driving 55 friction cone 148 is located between said cones and is arranged to be moved from a normal neutral position in opposite directions into driving engagement with one and the other of said driven cones. Said driving cone is fixed to a shaft 150 which is connected through a universal joint 152 with the secondary shaft 104. The shaft 150 adjacent said cone 148 is journaled in an 60 eccentric bushing that is or can be similar to the bushing 108 of the drive shaft for reciprocating the saw. Thus rotation of the bushing in opposite directions effects the movement of the driving cone 148 alternately into driving engagement with the driven cones 144 and 146. When the 65 driving cone 148 is in driving engagement with the cone 146 the rotation of the feed rolls is such as to advance the log toward the saw. When the driving cone is in driving engagement with the other cone the feed rolls are reversely rotated and the log is moved in the opposite direction.

The driving engagement between the cones is 70 under control of an operative. The eccentric bushing which supports the drive shaft 150 is connected to one end of a link 154, the other end of which is pivotally connected to an arm 156 of a shaft 158 extended longitudinally of the sled and passing loosely through the aforesaid operating 75 tube 120. Said shaft has a hand lever 160 fixed

thereto adjacent the handle 122. By moving the lever 160 outwardly from a neutral position or toward an operative standing beside the sled the driving cone 148 is moved from a neutral position into engagement with the driven cone 146 to advance 5 the log toward the saw. When the lever is moved away from the operative and into the neutral position the driving cone is operatively disconnected from both driven cones and hence the log feed is idle. When the lever is moved further 10 away from the operative the driving cone is brought into driving engagement with the reverse drive cone 144 and the log is retracted away from the saw. An operative standing at the position 15 of the hand levers 122 and 160 thus has full control of the operation of the machine and can advance the log by any desired amount over the deck 42 and cut it off from the remaining portion of the log. Usually, however, the logs are all cut to the same dimensions, usually in four foot lengths, 20 suitable for conversion into pulp wood.

The apparatus is provided with a stop member 25 which functions as a gauge to determine the length of the short logs. Said stop member comprises a bar 162, see especially Figs. 2, 3 and 5, 30 which is located at the end of the deck and is pivoted at 164 to the rear side edge of the sled and can be raised about its pivot by the operative to the position illustrated in Fig. 5 where the forward end thereof is disposed in the path of advance 35 of the log to limit the advance thereof and thereby define the length of the section to be severed from the body of the log. The stop member can also be lowered sufficiently to permit the severed short section of log to be withdrawn over it 40 and removed from the saw deck.

The raising and lowering of the stop member is effected by a foot pedal 166. Said pedal is 45 fixed to a shaft 168 journaled on the front girder 14 of the sled and having a rearwardly extended arm 167 the end of which is pivotally connected through a link 170 to the stop member 162. Thus the depression of the pedal serves to elevate the stop member and the weight of the stop member 50 serves to drop the member downwardly when pressure on the pedal is relieved. The weight of the stop member is approximately, although not entirely, counter-balanced by a counter-balancing lever 172 pivoted to a transverse member of the frame and pivotally connected at one end through 55 a link 174 with the stop member. The other end of the lever has a weight 176 thereon which acts through the lever and link to oppose, although not completely, the weight of the stop member. Thus the labor of elevating the stop member is reduced. The weight of the stop arm normally 60 maintains the pedal and balance lever 172 in elevated position so as to provide good clearance above the ground when the sled is being moved about.

The trailer sled 12 is provided with a set of feed rolls 178 similar or identical with the feed rolls 32 and journaled on the frame of the sled. A guide plate 180 similar to the guide plate 34 is located above the inner ends of the feed rolls and is suitably supported on the frame of the sled. The feed rolls are driven at equal speeds through gearing connecting them with a shaft 182 that is 70 extended lengthwise of the sled below and behind the plate 180. Said shaft 182 has a geared connection with and is driven by a shaft 184, see especially Fig. 9, that is supported crosswise of the sled and extends beyond the rear side thereof. Said shaft is driven from the cross shaft 138 of the saw sled, the shafts having equal diameter sprock- 75

et wheels 186 and 188, respectively, that is encircled by a driving chain 190, see especially Fig. 1, so that the feed rolls of both sleds are driven in the same direction at equal speeds. The length of 5 the chain 190 can be extended at will by inserting additional links so that the spacing between the two sleds may be made anything desired. If there is a relatively great spacing between the two sleds as may be desirable for operation upon exceptionally long logs, it may be desirable to position a 10 suitable support, not necessary to illustrate, carrying idler rolls between the two sleds so as to prevent having a long unsupported overhanging length of pole. It is not necessary to align the 15 two sleds accurately for handling the logs as the trailer sled can be misaligned moderately with respect to the saw sled and yet assist in advancing the log. Precise alignment of the feeding faces of all the feed rolls of the two sleds is not 20 necessary. For some purposes, such as when handling light logs, it is not necessary to drive the trailer sled rolls 178, as the rolls can be freely 25 rotatable idler rolls.

Thus it will be apparent that I have provided a 25 portable log sawing machine suitable for the conversion of long logs into pulp wood dimensions, which machine can be drawn along the usual winding, narrow and rough logging roads and over rough ground from one yard to another and positioned beside the log piles to cut the logs into pulp wood in a very satisfactory manner. A crew 30 of five men, two at the log pile transferring logs to the machine, one controlling the operation of the machine, and two removing the sections of logs from the machine and piling them, can readily produce fifty cords of pulp wood a day.

I claim:

1. A portable log sawing machine comprising 40 log supporting saw and trailer sleds having an articulated connection between them, a swing saw and a power plant on said saw sled, said saw being located near the free end of said saw sled, log advancing means on both sleds and both operative on the same log for advancing it to said 45 saw, and means interconnecting said sleds for

operating said log advancing means of both sleds conjointly.

2. A portable log sawing machine comprising 5 relatively long and narrow saw and trailer sleds having means connecting them flexibly and detachably in tandem, a swing saw and a power plant on said saw sled, said saw being located near the free end of said saw sled, both sleds having log advancing means operative upon the same log to pass it from one section to another 10 and to advance it to said saw, and means establishing a driving connection between the log advancing means of said sleds, the driving connection means being flexible to permit a small amount 15 of longitudinal misalignment between said sleds while maintaining an operative driving connection therebetween.

3. A portable log sawing machine comprising a 20 relatively long and narrow saw sled, a swing saw at one end of said sled mounted for swinging movement transversely of the sled, a series of log 25 conveyor rolls extended lengthwise of the sled adjacent one long side thereof, a roll driving shaft extended lengthwise of and having driving connections with said rolls, a drive shaft extended lengthwise of the sled adjacent the other long side thereof and having at one end a driving connection with said saw, a power plant located at the end of the sled opposite said saw approximately in line and having a driving connection 30 with the other end of said drive shaft, a feed shaft extended lengthwise of the sled and located between said drive shaft and roll driving shaft and having a driven connection with said drive shaft, 35 disengageable driving connections between said feed shaft and said roll driving shaft and between said feed shaft and the swing of said swing saw, a cross shaft located on said saw sled transversely thereof at the end having said power plant, a driving connection between said cross shaft and 40 said roll driving shaft, a trailer sled having a series of log conveyor rolls thereon, a cross shaft on said trailer sled for driving said rolls, and flexible means for establishing a detachable driving 45 connection between said cross shafts.

JOHN E. MCLEOD.
